13 Claims. (Cl. 66—111)

This invention relates to knitting machines equipped with independent latch needles, and has for its object to provide in such machines means of a simple and efficient character for preventing the latches of predetermined empty needles in a set from being open, and thereby ensuring that those needles do not take yarn and knit, at a yarn feeding location.

By an "empty" needle is meant one which has no loop around its stem or in its hook. Accordingly, although the invention is applicable to any knitting machine in which the latches of desired empty needles are deliberately closed to prevent said needles from knitting, it is principally the intention to employ the invention in a machine adapted to carry out the particular method of knitting described and claimed in our prior United States Patent No. 2,442,442 that is to say a method consisting of closing the latches of needles in a set, thereafter opening the latches of some of the needles of the set while the latches of the remaining needles of the set are kept closed, and feeding yarn to the needles so that those with open latches take the yarn and knit whilst the needles with closed latches do not knit by reason of the yarn being prevented from entering the hooks of those needles.

By such methods of knitting various conventional stitch effects including, for example, press-off, miss stitch, and purl stitch effects, or any desired combination of such effects, can be produced.

Now whenever latches of empty latch needles are closed and not required to knit, there is a tendency, especially when using certain yarns, for loose or trailing fibres to become trapped in front of the closed latches and for these fibres to open the latches so that, contrary to requirements, yarn is taken by the empty needles at the next yarn feeding location. Again, closed latches of empty needles sometimes tend to be shaken at least partially open, with the same consequences, by reason of the operating butts on the said needles, or on associated jacks or sliders, being jolted by contact with uneven edges of a cam race. Accordingly, an aim of this invention is to overcome these difficulties.

The means constituting the invention comprise a series of latch controlling members mounted for movement independently in a carrier which is arranged or arrangement adjacent to a needle bed containing a set of needles, the latches of predetermined empty ones of which are required to be closed at a yarn feeding location, the said carrier being adapted to be driven in suitable timed relation with the relative movement between the needle bed and the associated cam system for operating the needles, and the latch controlling members being selectively operable to control the latches of the aforesaid predetermined empty needles of the set.

With the knitting machine in operation, the carrier is so driven that the operative ends of the latch controlling members therein move seriatim across the leading ends of successive needles in the set. The construction and arrangement are such, moreover, that whenever a latch-controlling member is selected its operative end will be automatically projected into such a position as to guard the latch of the relevant empty needle and positively prevent this latch opening at the yarn feeding location, the operative end of each non-selected latch controlling member in the carrier, on the other hand, is permitted to remain clear of the latch of the appropriate needle, thereby enabling this latch, previously opened by an old

2

loop on the needle as the latter was advanced to clearing position, to be turned over and closed by the said loop upon subsequent retraction of the needle to knocking-over position. Thus, as will be appreciated, when the needles of the set are retracted seriatim to knocking-over position the fed yarn will be taken and formed into stitches only by the needles with open hooks, and will merely pass to the back of the predetermined empty needles with the closed hooks. The means of this invention therefore positively prevent the latches of these empty needles from being open at the yarn feeding location.

In this last regard, if the latch of an empty needle happens to be partially open as the needle approaches the yarn feeding location, then the operative end of the relevant selected latch controlling member will, as it is projected into its latch guarding position and moves laterally across the needle, contact the partially open latch and close the same with a camming action. Consequently, if the cause of the latch being partially open is the presence in front of the same of yarn fibres, then the closure of the latch by the latch controlling member may also result in the cutting of the fibres by a scissor action. Accordingly, the expression "controlling" used in this specification with reference to latches which are required to be closed, includes not only guarding closed latches to prevent them opening, but also, where necessary, first closing partially open latches.

Broadly speaking, the invention may be applied to knitting machines having but a single needle bed equipped with one set of needles, although it is principally the intention to apply it to a rib knitting machine having at least two opposed needle beds with a set of needles in each. Thus the invention is applicable to circular rib knitting machines of the cylinder and dial type as well as to flat machines of the Lamb type having relatively inclined needle beds; also to links and links (purl stitch) machines both circular and flat.

In a convenient embodiment of the invention, the aforementioned carrier is in the form of a rotary wheel or drum which is radially tricked to receive independent latch controlling members consisting of relatively thin blades arranged for movement pivotally within the tricks. In this embodiment provision of any suitable character is made for continuously rotating the wheel or drum adjacent to the needle bed, or the appropriate needle bed, of the machine at a speed commensurate with that of the said bed, or of its associated cam system, depending on the type of machine concerned. Moreover the operative ends of the latch controlling blades in this embodiment may advantageously extend outwardly from the rotary wheel or drum, the blades being normally so positioned in the tricks that the operative ends of un-selected blades are disposed well clear of needle latches as the wheel or drum revolves. When selected, however, blades tilt or cant outwardly with respect to the axis of the wheel or drum as a consequence of which their operative ends are moved into latch controlling position.

The pivoted latch controlling blades may conveniently be provided with operating butts adapted to be acted upon by blade-selecting means of any suitable character, and relatively fixed cam means may be provided to push back and thus restore selected blades to their normal positions after they have performed their function. In this regard, it will be appreciated that any one of the blades, when selected, serves to control one latch only for the comparatively short duration of time that the relevant needle is passing, or is being passed, by the yarn feeding means.

The invention may advantageously be applied to a knitting machine equipped with means for transferring loops or stitches from certain needles to others combined with means for closing the latches of needles from which the transfer has been effected. Thus, in a machine with a single set of needles, the transfer may be effected from desired needles to adjacent needles, and in a machine with at least two sets of needles from needles in one set to needles in the other set. In this latter connection the latch controlling members may, where practicable, be selectively operated to control closed latches of predetermined needles in one set by contact with needles of the other set selected to knit.

In order that the invention may be more clearly understood and readily carried into practical effect, a specific constructional example thereof applied to a circular knitting machine of the cylinder and dial type will now be described with reference to the accompanying drawings, wherein,

Figure 1 is a vertical sectional view of so much of such a machine as is necessary to illustrate the application thereto of a pattern selected latch control unit constructed and operable in accordance with the invention, 10

Figures 2 and 3 are sectional plan views taken respectively on the lines 11—11 and 111—111 of Figure 1,

Figure 4 is a detail underside plan view, as seen in the direction of the arrow A in Figure 1, illustrating the driving disc of the latch control unit, 15

Figure 5 is a perspective view of one of the latch controlling blades per se,

Figure 6 is a detail side view of one of the said blades shown in relation both to an inoperative cylinder needle and a companion dial needle, and

Figure 7 is a diagram depicting a few inoperative and selected cylinder needles, shown in relation to the centre line of the rotary latch control unit, this figure serving to facilitate a description of the manner in which the latch controlling blades are selectively operated.

Like parts are designated by similar reference characters throughout the drawings.

The machine illustrated in Figure 1 includes a rotary needle cylinder 1 equipped with independent latch needles 2, and a co-operating rotary dial 3 equipped with independent dial needles 4 also of the latch type. The stationary cylindrical cam box which surrounds the needle cylinder 1 and serves to house the cam system (not shown) for operating the cylinder needles 2 is indicated at 5, whilst at 6 is shown the conventional fixed dial cam cap serving to support the cam system for operating the dial needles 4. In the example illustrated, each of the cylinder needles 2 has associated therewith a loop transferring instrument 7, and, similarly, every dial needle 4 is associated with a loop transferring instrument 8.

Immediately in advance of the yarn feeding location at each feeder of the machine, there is provided a pattern selected latch control unit which is designated generally by the numeral 9 and includes a radially tricked rotary wheel 10 arranged for rotation about a vertical axis *a* in a bracket 11 mounted upon the top of the cylinder cam box. Located in the vertical tricks of the cylinder cam box. Located in the vertical tricks 12 are latch controlling blades 13 the longitudinal stems 13a of which extend more or less vertically in front of the cylinder needles 2 and the loop transferring instruments 7 associated therewith. At their upper ends these stems are formed with outwardly directed operative ends 13b which, as shown most clearly in Figures 5 and 6, extend substantially at right angles thereto and project from the tricks 12 in the wheel 10 (see Figure 1). The rear edges of the blade stems are so angularly formed as to provide thereon fulcrum points 14 about which the latch controlling blades 13 can rock. Secured to the lower end of the rotary wheel 10 by means of screws 15 is a peripherally toothed driving disc 16 arranged to mesh with the stems 2a and 7a of the cylinder needles 2 and the loop transferring instruments 7 so that as the cylinder 1 and the dial 3 of the machine rotate together, the wheel 10 will be driven from the cylinder at a commensurate peripheral speed. As illustrated in Figure 4, the screws 15 serving to secure the driving disc 16 to the underside of the wheel 10 extend through arcuate slots 17 in the said disc so that the latter, during assembly of the unit can be initially adjusted, circumferentially, with respect to the wheel. This adjustment enables the latch controlling blades 13 to be accurately set in relation to the stems of the cylinder needles. But when once this initial adjustment has been effected the driving disc is permanently fixed to the tricked wheel 10 by means of a dowel 18 driven into suitably drilled axially aligned holes (see Figures 1 and 4). The radially tricked outer portion of the wheel rests upon the top of inwardly directed unit-supporting part 11a of the bracket 11. The lower end of the centrally bossed portion 10a of the wheel 10 is embraced by a ring 19 which serves to retain the blades 13 in the wheel and is mounted to revolve in a circular bearing hole formed in the part 11a of the bracket. The top side of the driving disc 16 is formed with a boss 16a which is spigoted into the underside of the retaining ring 19. As will be appreciated, the tightened screws 15 exert the pressure

necessary to clamp the ring 19 firmly in position between the driving disc and the wheel 10. Depending from a plate 20 which is attached by screws such as 21 to the top of an upper horizontal portion 11b of the bracket 11 is a fixed, vertically disposed bearing pin 22 which extends down into a central bore 23 formed in the boss 10a of the tricked wheel 10. As shown in Figure 1, a thrust washer 24, fixed in position by means of the screws 21 and also by an additional screw or screws such as 25, is interposed between the underside of the portion 11b of the bracket and the upper edges of the latch controlling blades 13. At their lower ends the stems 13a of the latch controlling blades 13 are formed with outwardly directed foot-like extensions 13c which project radially from the tricked wheel and at their outer extremities are bent laterally to provide butts 13d adapted to be acted upon by selected cylinder needles 2 and their associated loop transferring instruments 7.

Normally, the latch controlling blades 13 are pressed back in their tricks 12 with their butts 13d upwardly inclined as shown at the left-hand side of Figure 1, and their operative ends 13b held up so as to be well clear of the latches 4a of dial needles 4 (see Figure 6). In this connection it will be appreciated from a consideration of Figure 2 that as the wheel 10 rotates, the operative ends 13b of the blades 13 move seriatim in an arcuate path across and above the leading ends of successive needles 4 in the dial 3. Each time a selected cylinder needle 2 and its transfer instrument 7 come round, however, they will act upon and press down the butt 13d of the relevant latch controlling blades 13, thereby selecting and canting the latter outwards with the result that its operative end 13b is swung outward and down to control the latch 4a of the next following empty dial needle as depicted at the right-hand side of Figure 1.

In this example, those cylinder needles which are "selected" are raised to take yarn and knit at a yarn feeding location F, whilst the un-selected needles remain down at a non-knitting level. This will be clear from Figure 7 wherein alternate pairs of the cylinder needles 2 are selected and the remaining intervening pairs are un-selected. Cylinder needles 2 selected to knit are raised in two stages, viz. first from the top of the cylinder verge at the level L to the intermediate level L¹ at which they function to press down the butts 13d of the relevant blades 13, and then from the said intermediate level to clearing height L². In Figure 7 the centre line or axis of the wheel 10 is indicated at *a*. The stems of the needles 2 and their associated needle transferring instruments 7 are widened to provide transfer shoulders 26, and it is the widened portions of these stems, adjoining the shoulders, which act on the blade butts 13d to press the latter downwards and inwards.

A relatively fixed return cam 27 carried by the bracket 11 is provided to press back selected blades into their tricks 12 after they have performed their function.

If desired, the stems of the blades 13 may be crimped to increase the frictional contact thereof with the walls of their tricks 12 and so prevent the blades from being too loose in the wheel 10.

The operative ends of the latch controlling blades 13 may be either straight, or laterally bent somewhat, according to requirements.

The invention includes, as a feature, a complete latch control unit per se for attachment to a machine.

I claim:

1. In a knitting machine, in combination, a needle bed, a set of independent latch needles for operation in said bed, the latches of predetermined empty ones of which are required to be closed at a yarn feeding location, a carrier which is arranged adjacent to the bed, an associated cam system for operating said needles, the carrier being driveable in timed relation with relative movement between the bed and the associated cam system, a series of latch controlling members which are mounted for movement independently in the said carrier, and means for selectively operating the said members to control the latches of the aforesaid predetermined empty needles of the set.

2. A combination according to claim 1, wherein the carrier is so arranged that, when it is driven, the operative ends of the latch controlling members therein move seriatim across the leading ends of the successive latch needles in the set.

3. A combination according to claim 2, wherein the

operative end of each selected latch controlling member is automatically projected into such a position as to guard the latch of the relevant empty needle and prevent this latch opening at the yarn feeding location, whereas the operative end of each non-selected latch controlling member is permitted to remain clear of the latch of the appropriate needle, for the purpose specified.

4. In a knitting machine, in combination, a needle bed, a set of independent latch needles for operation in said bed the latches of predetermined empty ones of which are required to be closed at a yarn feeding location, a rotary wheel which has radial tricks formed therein and is arranged adjacent to the bed, an associated cam system for operating the needles, the said wheel being continuously rotatable in timed relation with relative movement between the bed and the associated cam system, a series of latch controlling members consisting of relatively thin blades arranged for movement pivotally within the tricks in the wheel, and means for selectively operating the said members to control the latches of the aforesaid predetermined empty needles of the set.

5. A combination according to claim 4, wherein the operative ends of the latch controlling blades extend outwardly from the rotary wheel, the said blades being so arranged in the tricks that the operative ends of unselected blades are disposed well clear of needle latches as the wheel revolves, whilst selected blades are tilted or canted outwardly with respect to the axis of the wheel as a consequence of which their operative ends are moved into latch controlling position.

6. In a knitting machine, in combination, a needle bed, a set of independent latch needles for operation in said bed the latches of predetermined ones of which are required to be closed at a yarn feeding location, a rotary wheel which has radial tricks formed therein and is arranged adjacent to the bed, an associated cam system for operating the needles, the said wheel being continuously rotatable in timed relation with relative movement between the bed and the said cam system, a series of latch controlling members consisting of relatively thin blades arranged for movement pivotally within the tricks in the wheel and provided with operating butts, blade-selecting means for action upon these butts whereby the members are selectively operable to control the latches of the aforesaid predetermined empty needles of the set, and relatively fixed cam means for pushing back and thus restoring selected blades to their normal inoperative positions after they have performed their function.

7. In a knitting machine, in combination, two needle beds, a set of independent latch needles for operation in each of said beds, means for transferring loops from needles in one set to needles in the other set, a carrier which is arranged adjacent to one of said beds, an associated cam system for operating said needles, the carrier being driveable in timed relation with relative movement between this bed and the associated cam system, and a series of latch controlling members which are mounted for movement independently in the said carrier and are selectively operable to control latches of predetermined empty needles in one set by contact with needles of the other set selected to knit.

8. In a knitting machine, in combination, a needle

cylinder, a set of latch needles for operation in said cylinder, a co-operating dial, a further set of latch needles for operation in said dial, a rotary wheel which has radial tricks formed therein and is arranged for rotation about a vertical axis adjacent to the cylinder, an associated cam system for operating said needles, the said wheel being continuously rotatable in timed relation with relative rotation between the cylinder and the associated cam system, a series of latch controlling members consisting of relatively thin blades arranged for movement pivotally within the tricks in the wheel with their stems extending in front of the cylinder needles and their operative ends projecting outwardly from the wheel over the leading ends of the dial needles, and means for selectively operating the said blades to control the latches of predetermined empty dial needles required to be closed at a yarn feeding location, the arrangement being such that the operative ends of unselected blades are disposed clear of dial needle latches as the wheel revolves, whilst selected blades are tilted outwardly with respect to the axis of the wheel as a consequence of which their operative ends are moved into latch controlling position.

9. A combination according to claim 8, wherein the rear edges of the blade stems are so angularly formed as to provide thereon fulcrum points about which the blades can rock.

10. A combination according to claim 8, wherein the lower ends of the stems of the latch controlling blades are formed with outwardly directed extensions which project from the wheel and are provided with butts adapted to be acted upon by selected cylinder needles.

11. A combination according to claim 10, wherein the latch controlling blades are normally pressed back in their tricks with their butts upwardly inclined and their operative ends held up so as to be clear of the latches of dial needles, the construction and operation being such that as the wheel rotates, the operative ends of the blades move seriatim in an arcuate path across and above the leading ends of successive dial needles, and each time a selected cylinder needle comes round it will act upon and press down the butt of the relevant latch controlling blade, thereby selecting and canting the latter outwards with the result that its operative end is moved to control the latch of the appropriate dial needle.

12. A combination according to claim 8, wherein there is provided at the lower end of the rotary wheel a peripherally toothed driving disc arranged to mesh with the cylinder needles so that as the cylinder and dial rotate together, the wheel will be driven from the cylinder at a commensurate peripheral speed.

13. A combination according to claim 8, wherein a cam box surrounds the cylinder, a bracket is mounted on the cam box, the rotary wheel being arranged in said bracket, and a fixed return cam carried by the said bracket is provided to press back selected blades into their tricks after they have performed their function.
